UNITED STATES PATENT OFFICE.

JACOB Z. MARINUS, JR., OF JERSEY CITY, NEW JERSEY, ASSIGNOR TO
CHARLES H. DOWNES, OF SAME PLACE.

DESIGN FOR A PENCIL-CASE CHARM.

Specification forming part of Design No. **11,271**, dated July 1, 1879; application filed May 16, 1879.
[Term of patent 7 years.]

To all whom it may concern:

Be it known that I, JACOB Z. MARINUS, Jr., of Jersey City, in the county of Hudson and State of New Jersey, have originated and designed a Pencil-Case Charm, of which the following is a full, clear, and exact description, reference being had to the accompanying drawing, making part of this specification.

This design relates to the ornamental case or enclosure for a pencil, watch-key, or toothpick, and is adapted to be hung from a watch-chain or guard as a charm.

A designates the leg portion of a gaiter-boot; b, the heel of the boot, and a a a row of buttons, about which latter is a line of scallops. The buttons and scallops may be omitted without destroying the character of my design.

C designates a barrel or tube protruding from the upper end of the boot-leg A, which barrel or tube is surmounted by an ornamental head, D, through the eye of which passes a ring, E.

F designates a pencil-nib protruding from the heel b of the boot in a line with the tube C.

The suspending-ring E, at the upper end of the tube C, gives a finished appearance when the pencil is opened or closed.

The boot may be made of a metal, a mineral, or a vegetable substance.

What I claim as new, and desire to secure by Letters Patent, is—

The design for the case described and shown, consisting of the form of a boot provided with tube C and ring E, exposed at the upper end or leg of the boot, and a pencil-nib, F, protruding from the heel of the boot, substantially in the manner above described.

JACOB Z. MARINUS, JR.
